(No Model.)

H. JONES.

PUMP.

No. 259,548.

Patented June 13, 1882.

Fig. 1.

UNITED STATES PATENT OFFICE.

HARRY JONES, OF STERLING, ILLINOIS.

PUMP.

SPECIFICATION forming part of Letters Patent No. 259,548, dated June 13, 1882.

Application filed April 10, 1882. (No model.)

To all whom it may concern:

Be it known that I, HARRY JONES, of Sterling, in the county of Whiteside and State of Illinois, have invented certain new and useful 5 Improvements in Pumps; and I do hereby declare that the following is a full, clear, and exact description of the invention, which will enable others skilled in the art to which it appertains to make and use the same, reference 10 being had to the accompanying drawings, which form a part of this specification, in which—

Figure 1 is a longitudinal vertical section of a pump embodying my improvement. Fig. 15 2 is a sectional view of the plunger on an enlarged scale, and Fig. 3 is a perspective view of the same.

Similar letters of reference indicate corresponding parts in all the figures. 20 My invention has relation to pump pistons or plungers, and is applicable alike to lifting-pumps and force-pumps, both double and single acting. In the accompanying illustration of my invention I have shown it as applied to 25 a single-acting lifting-pump; and the nature of my improvement consists in so constructing the plunger that it shall be self-packing or water-packing, by creating two currents of water (or air) flowing simultaneously in opposite directions and meeting between the pump barrel and piston along its entire stroke, substantially as hereinafter more fully set forth.

In the accompanying drawings, A represents 30 the pump-barrel, which has the usual valve and valve-seat (shown respectively at a and b) in the bottom, and the water-pipe A', which reaches down into the well or cistern.

B is the sucker-rod, which is hinged in a 35 bail, b', in the upper end of the plunger C. The latter is of cylindrical shape, open at the top, having a convex valve-seat, c, and ball-valve d in its perforated bottom. The valve is held in place within its cage or chamber e by 40 a cross-bar, f, or any other suitable means. The outside of the plunger has three circumferential grooves or channels, (shown respectively at g, h, and i.) The middle channel, h, is 45 deeper than the top and bottom channels, g and i, and has a series of ducts or apertures, k, which extend from it in an oblique direc-

tion through the wall of the plunger. The slant or obliquity of these ducts is of importance, for the reason hereinafter stated. The plunger (which may be made of wood or metal) 55 should be of such diameter that it will work easily within the pump-barrel without friction, or with a minimum of friction, and the top and bottom grooves or channels, g and i, are left clear or without packing. On the upstroke of 60 the plunger water enters the pump-barrel through the suction-pipe A' and its valve, and on the downstroke water enters the plunger through its bottom valve. On the next upstroke the pressure of the water above the 65 plunger causes a film of water to be forced from the top into the narrow cylindrical space between the plunger and pump-barrel, as shown by the small arrows marked x; but by the same motion of the plunger the resistance 70 of the column of water above this will cause a jet of water to be thrown into an oblique upward direction through the slanting ducts k from the inside of the plunger out into the narrow space between the plunger and pump-barrel, as indicated by the arrows marked y; but here these currents meet the downward currents x, when a water packing or cushion will in this manner be formed at a point, or rather on a line, intermediate between the channels g and h, which will move with the piston. 75 This is repeated with each upstroke, the top and bottom grooves, g and i, forming dead-water chambers, which assist in equalizing the pressure of the two meeting currents x and y. 80

By reversing the plunger in its working-barrel and changing the position of the valves in the latter in a manner well understood my improved plunger may be used with force-pumps with the same advantage as with lifting-pumps, and will always, owing to the absence of packing, be found to work with a minimum of wear and friction. 90

Having thus described my invention, I claim and desire to secure by Letters Patent of the 95 United States—

1. In a pump, the hollow plunger C, of cylindrical shape, having valve d, valve-seat c, top and bottom-channels, g and i, and central annular channel, h, and provided with oblique 100 ducts k, slanting from the intermediate annular chamber or channel, h, in a downward di-

rection toward the interior of the hollow plunger, substantially as and for the purpose herein shown and set forth.

2. In a hollow pump-plunger having a valve and valve-seat of suitable construction, a series of ducts, *k*, opening obliquely from the inside of the hollow valve to an annular chamber or channel, *h*, on its outside, substantially as and for the purpose herein shown and set forth.

In testimony that I claim the foregoing as my own I have hereunto affixed my signature in presence of two witnesses.

HARRY JONES.

Witnesses:

LOUIS BAGGER,
AUGUST PETERSON.
